UNITED STATES PATENT OFFICE.

OSCAR A. ROSS, OF CHICAGO, ILLINOIS, ASSIGNOR OF ONE-HALF TO C. VALLETTE
KASSON, OF CHICAGO, ILLINOIS.

AUTOMATIC TRAIN STOP OR SIGNAL DEVICE.

1,101,511.

Specification of Letters Patent. Patented June 23, 1914.

Application filed July 12, 1907. Serial No. 384,547.

To all whom it may concern:

Be it known that I, OSCAR A. ROSS, a citizen of the United States, residing at Chicago, county of Cook, and State of Illinois, have invented certain new and useful Improvements in an Automatic Train Stop or Signal Device, of which the following is a description.

My invention relates to that class of devices adapted for use upon railway lines or the like to indicate to the engineer or other suitable person having control of the movements of a train or vehicle upon a track, the presence of another vehicle upon the same track or some derangement of the track or apparatus which might render it necessary or desirable to stop or to proceed with caution.

The object of my invention is to provide a simple, durable, and effective device of the kind described arranged to indicate its own condition as well as that of the adjacent track to which it is applied so that there is no chance of the person in the control of the train or vehicle relying upon the operation of a wholly or partially inoperative device with the possible attending disastrous consequences.

To this end my invention consists in the novel construction, arrangement, and combination of parts, herein shown and described and more particularly pointed out in the claims.

In the accompanying drawings wherein like or similar reference characters indicate like or corresponding parts, Figure 1 is a diagrammatic view showing the arrangement of the conductors and associated parts of the rail circuit for a double track road. Fig. 2 is a view similar to Fig. 1, but showing the changes produced in the mechanism by the presence of a vehicle upon the track. Fig. 3 is a diagrammatic view of the circuit and associated parts upon the vehicle. Fig. 4 is a side detailed elevation of the preferred form of contact shoe. Fig. 5 is an end elevation of a brake, or signal operating mechanism. Fig. 7 is a section taken substantially on line 7-7 of Fig. 8, and Fig. 8 is a section taken substantially on line 8-8 of Fig. 6.

To put my system into operation upon a road, the rails composing the track are preferably first divided into sections or blocks as 1, 2, 3 and 1', 2' and 3' each section being

preferably from a part of one mile to several miles in length, the rails thereof being carefully insulated from the rails of the adjacent section, and the rails at one side of the track from those at the opposite side. The several rail members composing each section are suitably bonded or otherwise electrically connected so that the rail forming each side of each section is adapted to serve as a continuous conductor extending the entire length of the section. In the form shown also, a contact bar 4 is provided adjacent the end of each section extending substantially parallel with the rails of the section, and electrically connected at one end to one of the rails of an adjacent track section by means of a suitable conductor 5 and at the opposite end connected by a conductor 6, stop 7 and conductor 8 to one terminal of the windings of an electromagnet 9. The other terminal of the magnet winding is connected by means of a conductor 10 to the opposite rail of the section to which the conductor 5 is attached.

In the drawings for the purpose of illustration, my mechanism is shown arranged to operate at the adjacent end of the section next preceding the section to which the conductors 10 and 5 are attached. It is obvious that by merely extending these conductors the magnet 9 and associated co-operating parts may be positioned at the end of, or at any preferred point in, the second preceding or any desired section in the track and operate in substantially the same manner as shown, except that the distance between the point where the signal is received and the dangerous section of track will be changed to that extent.

Any suitable source of electric energy may be provided for operating the track circuit above described. In the form shown a battery 11 is provided for each section and connected by means of the conductors 12 and 14 to the opposite rails of the section respectively. The contact bar 4 and associated parts above described being preferably so positioned that a vehicle after arriving at the bar 4 at the end of a section may be brought to a stop before entering the next succeeding section. The direction of vehicles upon the tracks being as indicated in the drawings by the arrows.

As shown and above described, it is ob-

vious that current supplied by the battery 11 will flow by means of the conductor 12, rail 2', conductor 5', contact bar 4' in the next section, conductor 6', stop 7', conductor 8' electromagnet 9' and conductor 10', rail 2 and conductor 14, back to the battery 11, thus completing the circuit through the electromagnet 9' and attracting the armature 15'. When however, a vehicle passes from the rails 1, 1' to the rails 2 and 2' closing the circuit directly between the rails 2 and 2', it is obvious that owing to the reduced resistance, in the new connection between the rails particularly after the connections between the conductors 5' and 10' with the rails 2' and 2 respectively are passed, the electric energy will cease to operate the magnet 9', and the armature 15' will be released permitting the same to be moved by a spring 5' or other suitable means into contact with the stop 7' thus closing a circuit directly between the rail 1 and contact bar 4' by means of the conductor 16', armature 15', stop 7' and conductor 6'. The parts will remain in the above described condition until the vehicle reaches the opposite end of the section 2 when the electro-magnet 9' and other associated parts will assume their normal condition, and the electro-magnet 9 and its associated parts for the next section operate as above described.

Any suitable means may be employed for utilizing the above described operations to operate a signal or other means for warning the operator of a train or vehicle upon a preceding section of the track that a certain section in advance is occupied. In the form shown each vehicle or train upon the track is provided with a suitable source of electric energy, as for example, a battery 17 (Fig. 3) connected by means of conductors 18 and 19 to a suitable signal operating device 20, adapted to operate whenever the circuit from the battery is opened or otherwise prevented from controlling its mechanism. The opposite pole of the battery 17 is connected by means of a conductor 21, shoe 22 and conductor 23 to the opposite pole of the device 20. A separate conductor 19 is suitably connected to the conductor 18 and extends to one of the trucks of the vehicle or other suitable part adapted to ground the circuit with the rails upon which the truck rests. With this arrangement it will be observed that with the track in normal condition, the vehicle merely serves to close the circuit between the rails of the track without affecting the circuit from the battery 17 upon the vehicle, the shoe 22 contacting with the bar 4 producing no effect upon the circuit so long as the bar 4 is not in electric contact with either of the rails of the track. Upon the operation of the track circuit as hereinbefore described however, to close the

circuit between the bar 4 and one of the rails of the track, it is obvious that the engagement of the shoe 22 with the bar 4 will short circuit the battery 17 practically depriving the signal operating device 20 of current and permitting the same to be operated in substantially the same manner as if its circuit were broken. The circuit when the engine shoe contacts with the track contact, the track circuit being operated as before mentioned, may be traced as follows: battery 17, line 21, contact 29, spring 28, shoe 27, track contact 4', line 6', stop 7', armature 15', line 16', rail 1, engine wheel, axle, wire 19, binding post 53, where it divides, part going back to the battery through spring 54, binding post 55 and wire 18, and part going back to the battery through electro-magnet 48, binding post 52, and wire 23, but the first path offering practically no resistance there is not enough current passing through the electro-magnet to cause it to attract its armature; therefore, it falls.

From the above description it is obvious that the breaking of a rail in the section ahead of a vehicle, the inundation of the tracks, the severing of any of the conductors, or any other accident liable to occur would be indicated at the bar 4 of a preceding section so that a vehicle thereon would have time to come to a stop before entering the damaged section. Also in case the shoe 22 upon the vehicle is broken away or the circuit to it broken, the device will operate the same as in the case of a vehicle upon the preceding section.

Any desired form of shoe may be provided upon the vehicle. In the form shown in Fig. 4 a suitable stationary part 24 upon the vehicle is provided, having a pair of projecting pins 25-25 one at each end extending therethrough adapted to receive the links 26-26, to the opposite end of which is attached a movable contact member 27. A spring 28 is preferably provided to resiliently force the contact member 27 away from the part 24 as shown in Fig. 4. The spring 28 is preferably attached to the part 27 and serves as a conductor between the plates 29-29 to which the conductors 21 and 23 respectively are connected, the bottom of the contact member 27 being adapted to contact with the upper surface of the bar 4.

Obviously when the contact member 27 encounters a bar 4 or any other object in its path tending to move it in either direction it will merely swing upon one of the links 26 the movement being permitted by the slotted opening 30 in the opposite link, the contact member remaining substantially parallel to its normal position.

Any desired form of signal operating device 20 may be provided and arranged to

operate any preferred kind of signal mechanism. As shown this portion of my device is adapted to operate in conjunction with the air brake mechanism upon the train or vehicle, to set the brakes when indicating the approach of danger, thus tending automatically to stop the vehicle when my device operates. In the form shown an enclosing casing 60 is provided having suitable doors or covers 61—61 upon its opposite sides to afford convenient access to its interior. The doors 61—61 are preferably hinged to the part 60 and secured in closed position by a bolt 62 or other suitable means. A threaded recess 31 is provided upon the part 60 for connecting the device to the train line of the brake system and an outlet opening 32 is provided connected to the recess 31 by means of a suitable port 33. A valve or slide 34 is provided to control the port 33 and thus the escape of air from the train line. The valve 34 may be of any suitable form or construction adapted for this purpose. In the form shown this valve consists of a cylindrical plunger snugly fitted to a suitably formed portion of the recess 31, the plunger 34 being preferably so formed that the pressure in the train line will tend to force the plunger inward and open the port 33, suitable means being provided to normally maintain the plunger 34 in position to prevent such movement. In the preferred construction shown, a stem or shank 35 is provided upon the plunger 34 slidably mounted in a suitable bearing 36 upon the frame 60 to guide the movement of the plunger. A bar 37 provided with an extension 38 hinged to its free end by means of a suitable screw or equivalent means 43 is pivotally connected at its opposite end to the plunger 34 as at 39 with the free end of the extension 38 positioned to engage a suitable stop or abutment 40 upon the frame 60 so that while the two parts 45 of the bar are in line, the plunger 34 will be rigidly maintained in its normal position. A spring 41 is also provided to partially control the movement of the plunger 34 when released by the movement of the bar 37 and a nut 42 or equivalent means is provided upon the stem 34 to adjust the pressure of the spring tending to hold the plunger in its normal position the pressure being preferably adjusted to merely check the too rapid movement of the plunger. To release the plunger 34 it is merely necessary to elevate the pivotal connection 43 between the bar and its extension. Any desired means may be provided for this purpose. As shown, the ends of the screw or pin 43 preferably extend beyond the outer sides of the bar and a pair of levers 44 are pivotally mounted upon the frame as at 45 one at each side of the bar 37 the levers each having a suitably formed lug or projection 46

upon their approximate faces positioned to engage the upper side of the extremities of the pin 43 and hold the bar 37 in its normal position preferably with its free end resting upon the upper face of the bearing 36. A second projection 47 is provided upon each of the levers 44 each projection positioned directly beneath the end of the bar 37 adjacent the pin 43 so that when the lever 44 is permitted to assume the position shown in broken lines in the drawing, the lugs 46 will first move from their position restraining the upward movement of the pin 43, when the lugs 47 will engage the bar 37 near its pivotal connection with the extension 38 and force the same upward releasing the plunger 34 as before described. In the preferred construction the lever 44 is maintained in its normal position by means of a suitable electro-magnet 48, the armature 49 of which is pivotally attached to any suitable part of the frame 60 and provided with a jaw 50 arranged to loosely engage a pin 51 or equivalent means extending between the levers 44 thus retaining the lever in position as long as the magnet 48 is energized but releasing the same by gravity as soon as the current to the magnet is interrupted or its potential sufficiently reduced.

The usual or any preferred means may be provided for attaching the conductors 18 and 23 to the magnet 48 of the signal operating mechanism 20 but it is obvious that in case the current from the battery 17 is short circuited as is hereinbefore described for any protracted period, the battery 17 will be ruined or its strength seriously impaired. To avoid this difficulty, means are provided for breaking the circuit as soon as the armature 49 is released owing to the short circuit. As shown, this is accomplished by connecting one terminal of the magnet 48 to a binding post 52 to which one of the conductors from the battery 17 is also attached, as for example, the conductor 23. The other terminal of the magnet 48 is connected to an auxiliary binding post 53 to which the ground wire 19 is attached, the binding post 53 being connected by a spring 54 to the main binding post 55 connected by the conductor 18 to the opposite pole of the battery. A suitable post or pin 56 or equivalent means suitably insulated from the armature 49 is provided upon the armature to engage the spring 54 and hold its free end in contact with the binding post 55 as long as the magnet 48 is energized.

If preferred, in order to prevent the too rapid discharge of air from the train line and the consequent danger of producing an emergency operation of the brake mechanism, an adjustable plug 57 may be provided in the outlet 32 to control the escape of air at the outlet.

Any suitable means may be provided to re-set the valve mechanism after the same has been released as above described. As shown a collar 63 is secured upon the stem 35 near its extremity beyond the bearing 36 and provided with a lug or wing 64 at each side of the stem. The lugs 64 are so positioned that they will engage the levers 44 and the position of the collar 63 upon the stem 35 is such that when the pressure is sufficiently reduced in the train pipe the spring 41 will move the plunger 34 inward until the lugs 64 will engage the levers 44 and limit the movement of the plunger and associated parts in that direction.

When the normal pressure is upon the train pipe the plunger is forced outward until it is arrested by the engagement of the jointed bar 38 with the wall of the casing 20 as previously described. When in this position the collar 63 is retracted to permit the release movement of the levers 44 and as the plunger and connected parts are immediately forced outward to the limit of their movement when released the levers are thereby permitted to fall to the position shown in broken lines in Fig. 8. As soon as the pressure in the train pipe is sufficiently reduced the plunger 34 advances and closes 30 the port 33 and slightly elevates the ends of the levers 44, a still further reduction of the pressure in the train pipe permits the plunger and connected parts to move still further inward levers 44 being engaged by 35 the lug 64 on the collar 63 thereby raising the levers and causing the pin 51 upon the levers 44 to engage the jaw 50, and upon a still further movement of the plunger to restore all of the parts to their normal positions so as to prevent any escape of air from the train line at this point and to positively maintain the parts in position until released as hereinbefore described.

In the foregoing description while the batteries 11 and 17 have been specifically referred to as the source of electric energy for controlling the operation of my mechanism, it is obvious that while suitable batteries may be used for this purpose, the 50 particular source of electric energy is immaterial and I do not therefore wish to be understood as limiting myself to any particular current producing means. In the drawings also my device is shown as applied 55 to a double track road and adapted for use upon vehicles moving in one direction only upon the track, it is obvious however that by slight modifications my invention may be applied to a single track road with equal 60 facility for protecting trains which may be moving in either direction upon the same track and it is therefore apparent that having thus described my improvement, various 65 immaterial modifications may be made in my device without departing from the spirit

of my invention, hence I do not wish to be understood as limiting myself to the exact form and construction shown.

What I claim as new and desire to secure by Letters Patent is,

1. In a device of the kind described, two normally closed electric circuits, and means adapted to be operated by one of said circuits to short-circuit the other circuit whenever the first mentioned circuit is short-circuited, said second circuit including means for opening the same when short-circuited.

2. In a device of the kind described, two normally closed electric circuits and means adapted to be operated by one of said circuits to normally short-circuit the other circuit whenever said first mentioned circuit is either opened or short-circuited, and means included in the second circuit adapted to open said second circuit as soon as the same is short-circuited.

3. In a device of the kind described, and in combination a track comprising a plurality of successive sections of substantially parallel rails insulated from each other and a closed electric circuit carried by a vehicle upon the track, an electric track circuit for each track section, each track circuit including means for short-circuiting said vehicle circuit, said means comprising one or more contact bars for each section included electrically in the track circuit of another section.

4. In a device of the kind described, and in combination a track comprising a plurality of successive sections of substantially parallel rails insulated from each other, and a closed electric circuit carried by a vehicle upon the track, an electric track circuit for each section, each track circuit including means for short-circuiting said vehicle circuit, said means comprising a contact bar for each section, arranged in the track circuit of another section, and a normally open electric connection between a rail in said track circuit and said contact bar.

5. In a device of the kind described, and in combination a track comprising a plurality of successive sections of substantially parallel rails insulated from each other, and a closed electric circuit carried by a vehicle upon the track, an electric track circuit for each section, each track circuit including means for short-circuiting said vehicle circuit, said means comprising a contact rail for each section, arranged in the circuit of another section and a normally open electric connection between a rail in said track circuit and said contact rail, and means adapted to open said vehicle circuit as soon as the same is short-circuited.

6. In a device of the kind described, a track comprising a plurality of successive sections of substantially parallel rails in

ulated from each other, two normally closed electric circuits, one circuit including a section of track, the other circuit carried by a vehicle mounted upon said track, each track circuit including means for short circuiting said vehicle circuit, said means comprising a contact bar for each section included in the track circuit of another section, a contact shoe carried by the vehicle and connected in the circuit upon the vehicle.

7. In a device of the kind described, a track comprising a plurality of successive sections of substantially parallel rails, insulated from each other, and an electric track circuit for each section, in combination with a contact bar for each section connected to the circuit of an adjacent track section, and means controlled by the circuit in which said bar is connected for electrically connecting said bar temporarily to one of the rails of its own particular track section.

8. In a device of the kind described, a track comprising a plurality of successive sections of substantially parallel rails insulated from each other, and an independent electric track circuit for each section, in combination with a contact bar for each section connected in the circuit of an adjacent track section and means controlled by the circuit in which said bar is connected for electrically connecting said bar temporarily to one of the rails of its own particular track section.

9. In a device of the kind described, a track comprising a plurality of successive sections of substantially parallel rails insulated from each other, and an electric track circuit for each section, in combination with a contact bar for each section positioned substantially parallel to said rails and connected in the circuit of an adjacent track section, and means controlled by the circuit in which said bar is connected for electrically connecting said bar temporarily to one of the rails of its own particular track section.

10. In a device of the kind described, a track comprising a plurality of successive sections of substantially parallel rails insulated from each other, in combination with a single contact bar positioned near the end of each section and connected in the circuit of an adjacent track section, and means controlled by the circuit in which said bar is connected for electrically connecting said bar temporarily to one of the rails of its own particular track section.

11. In a device of the kind described, a track comprising a plurality of successive sections of substantially parallel rails insulated from each other, and an electric track circuit for each section, in combination with a single contact bar positioned parallel to, and between, the rails near the end of each section, and connected in the circuit of an

adjacent track section, and means controlled by the circuit in which said bar is connected for electrically connecting said bar temporarily to one of the rails of its own particular track section.

12. In a device of the kind described, a track comprising a plurality of successive sections of substantially parallel rails insulated from each other, and an electric track circuit for each section, in combination with a contact bar for each section connected in the circuit of an adjacent track section, and a relay controlled by the circuit in which said bar is connected for electrically connecting said bar temporarily to one of the rails of its own particular track section.

13. In a device of the kind described, a track comprising a plurality of successive sections of substantially parallel rails insulated from each other, and an electric track circuit for each section, in combination with a contact bar for each section connected in the circuit of an adjacent track section, and means controlled by the circuit in which said bar is connected and adapted to be operated by the short-circuiting of said circuit for electrically connecting said bar temporarily to one of the rails of its own particular track section.

14. In a device of the kind described, a track comprising a plurality of successive sections of substantially parallel rails insulated from each other, and an independent electric track circuit for each section, in combination with a contact bar for each section, positioned substantially parallel to said rails and connected in the circuit of an adjacent track section and means controlled by the circuit in which said bar is connected for electrically connecting said bar temporarily to one of the rails of its own particular track section.

15. In a device of the kind described, a track comprising a plurality of successive sections of substantially parallel rails insulated from each other, and an independent electric track circuit for each section in combination with a single contact bar positioned near the end of each section and connected in the circuit of an adjacent track section, and means controlled by the circuit in which said bar is connected for electrically connecting said bar temporarily to one of the rails of its own particular track section.

16. In a device of the kind described, a track comprising a plurality of successive sections of substantially parallel rails insulated from each other, and an independent electric track circuit for each section, in combination with a single contact bar positioned parallel to, and between, the rails near the end of each section and connected in the circuit of an adjacent track section, and means controlled by the circuit in which

said bar is connected for electrically connecting said bar temporarily to one of the rails of its own particular track section.

17. In a device of the kind described, a track comprising a plurality of successive sections of substantially parallel rails insulated from each other, and an independent electric track circuit for each section, in combination with a contact bar for each section connected in the circuit of an adjacent track section, and a relay controlled by the circuit in which said bar is connected for electrically connecting said bar temporarily to one of the rails of its own particular track section.

18. In a device of the kind described, a track comprising a plurality of successive sections of substantially parallel rails insulated from each other, and an independent electric track circuit for each section, in combination with a contact bar for each section connected in the circuit of an adjacent track section, and means controlled by the circuit in which said bar is connected and adapted to be operated by the short-circuiting of said circuit for electrically connecting said bar temporarily to one of the rails of its own particular track section.

19. In a device of the kind described, a track comprising a plurality of successive sections of substantially parallel rails insulated from each other, and an independent electric track circuit for each section, in combination with a contact bar for each section positioned substantially parallel to said rails and connected in the circuit of an adjacent track section, and a relay controlled by the circuit in which said bar is connected for electrically connecting said bar temporarily to one of the rails of its own particular track section.

20. In a device of the kind described, a track comprising a plurality of successive sections of substantially parallel rails insulated from each other, and an independent electric track circuit for each section, in combination with a contact bar for each section positioned substantially parallel to said rails and connected in the circuit of an adjacent track section, and means controlled by the circuit in which said bar is connected and adapted to be operated by the short-circuiting of said circuit for electrically con-

nnecting said bar temporarily to one of the rails of its own particular track section.

21. In a device of the kind described, a track comprising a plurality of successive sections of substantially parallel rails insulated from each other, and an independent electric track circuit for each section, in combination with a single contact bar positioned substantially parallel to, and between, the rails near the end of each section and connected in the circuit of an adjacent track section, and a relay controlled by the circuit in which said bar is connected for electrically connecting said bar temporarily to one of the rails of its own particular track section.

22. In a device of the kind described, a track comprising a plurality of successive sections of substantially parallel rails insulated from each other, and an independent electric track circuit for each section, in combination with a single contact bar positioned substantially parallel to, and between, the rails near the end of each section and connected in the circuit of an adjacent track section, and a relay controlled by the circuit in which said bar is connected and adapted to be operated by the short-circuiting of said circuit for electrically connecting said bar temporarily to one of the rails of its own particular track section.

23. In a device of the kind described, a track comprising a plurality of successive sections of substantially parallel rails insulated from each other, and an independent electric track circuit for each section, in combination with a single contact bar positioned substantially parallel to, and between, the rails near the end of each section, and connected in the circuit of an adjacent track section, and means controlled by the circuit in which said bar is connected and adapted to be operated by the short-circuiting of said circuit for electrically connecting said bar temporarily to one of the rails of its own particular track section.

In testimony whereof, I have hereunto signed my name in the presence of two witnesses.

OSCAR A. ROSS.
